UNITED STATES PATENT OFFICE.

FRANCIS A. SAWYER, OF BOSTON, MASSACHUSETTS.

CARRIAGE-STEP.

SPECIFICATION forming part of Letters Patent No. 314,151, dated March 17, 1885.

Application filed January 8, 1884. Renewed February 17, 1885. (No model.)

To all whom it may concern:

Be it known that I, FRANCIS A. SAWYER, of Boston, in the county of Suffolk and State of Massachusetts, a citizen of the United States, 5 have invented a new and useful Improvement in Carriage, Car, and other Steps, of which the following is a full, clear, and exact description, reference being had to the accompanying drawings, forming a part of this specification in explaining its nature, in which—

Figure 1 represents in perspective a carriage-step containing my improvement. Fig. 2 is a vertical section thereof. Fig. 3 represents a modification which is hereinafter specially referred to.

The invention relates especially to a step having an ornamental upper surface or tread, the more ornamental part of which is so placed and sheltered as to be protected from the wear 20 to which the other portion of the step or tread is submitted.

Referring to the drawing, A is the step. It is divided into the sections a a' . The section a comprises the front portion of the step, and 25 is that part which is most subjected to wear, and preferably it has a ribbed or pyramidal surface, or a surface of any other similar character. The section a' is that portion of the step or tread back of the section a , and is the 30 portion of the tread which is subjected to but little if any wear. This section is highly ornamental, and may be, if desired, sunk below the level of the section a , so that the sole of the boot or shoe of the user of the step can 35 not come in contact with it until the section a is worn away sufficiently to permit it.

I do not confine myself in the use of this invention to steps made of metal, but may use it in steps made of rubber or other formative

material; and when rubber or other like material is employed it is reamed to the step-plate in any of the ways described in my patents; and I prefer to raise the level of the front section, a , for two reasons—first, to more effectually protect the highly ornamented part 40 or section a' , and, second, to use as little stock as possible in section a' , which is not subjected to wear, and to put what is not required there into the section a , where it will be of service—and by so doing I not only get a very 45 ornamental step, but I also utilize the material of the step to the best advantage. This feature will also apply to metal steps.

Of course any suitable ornamentation may be used in section a' , or a monogram or name 50 or words of any character can be used in lieu of the ornamentation, and the effect of the invention will remain the same.

Having thus fully described my invention, I claim and desire to secure by Letters Patent 55 of the United States—

1. A step having a wearing or treading surface and an ornamental section disposed in relation to each other, as and for the purposes described.

2. In a step, the combination of the wearing or tread section a and the ornamental section a' , substantially as and for the purpose described.

3. A step having the ornamental section a' 65 and the tread or wearing surface a^2 , extended above the upper surface of the ornamental section, all substantially as and for the purposes described.

FRANCIS A. SAWYER.
